CLAIM

The ornamental design for a refillable chemical reservoir, as shown and described.

DESCRIPTION

FIG. 1 is a perspective view of a first embodiment of a refillable chemical reservoir according to the invention;

FIG. 2 is a front elevational view thereof;

FIG. 3 is a rear elevational view thereof; the rear elevational view of embodiment 2 being identical;

FIG. 4 is a left side elevational view thereof, the left side elevational view of embodiment 2 being identical;

FIG. 5 is a top plan view of embodiment 1, the top plan view of embodiment 2 being identical;

FIG. 6 is a bottom plan view thereof, the bottom plan view of embodiment 2 being identical;

FIG. 7 is a perspective view of a second embodiment of a refillable chemical reservoir according to the invention;

FIG. 8 is a front elevational view thereof; and,

FIG. 9 is a right side elevational view thereof.

The broken lines shown in the drawings are included for the purpose of illustrating environmental structure that forms no part of the claimed design.
